UNITED STATES PATENT OFFICE.

WILLIAM T. MAGNESS, OF SPARTANBURG, SOUTH CAROLINA.

CRACKER-CASE.

SPECIFICATION forming part of Letters Patent No. 754,326, dated March 8, 1904.

Application filed June 18, 1903. Serial No. 162,060. (No model.)

To all whom it may concern:

Be it known that I, WILLIAM T. MAGNESS, a citizen of the United States, and a resident of Spartanburg, in the county of Spartanburg 5 and State of South Carolina, have made certain new and useful Improvements in Cracker-Cases, of which the following is a specification.

My invention is an improvement in cracker-cases or cases for holding boxes of crackers; 10 and the invention consists in certain novel constructions and combinations of parts, as will be hereinafter described and claimed.

In the drawings, Figure 1 is a perspective view of a portion of a case provided with my 15 improvements. Fig. 2 is a partial vertical longitudinal section thereof. Fig. 3 is a bottom view of one of the sliding shelves, showing the means for locking the same in its different positions, and Fig. 4 is a detail view of the 20 bolt and its spring.

By my invention I provide in a case of the character shown a framing provided with guides in which slide the shelves for supporting the cracker-boxes, so the shelves can be 25 adjusted out of the frame to permit access to the boxes and can be adjusted back in their guides to carry the cracker-boxes into the frame when it is desired to store the same. In connection with the sliding box-supporting 30 shelves I provide lock devices for securing the shelves in their different positions and jointed links connecting the outer ends of the sliding shelves with the casing to aid in guiding the movements of the shelves and in supporting the same when adjusted to their outer 35 positions.

In the construction shown the case A is provided with the guides B for the sliding shelves C, and has at D and at D' seats for the locking-bolts carried by the shelves, so said shelves 40 may be locked in their inner positions, as illustrated by the upper shelf in Fig. 2, and in their outer positions, as illustrated by the lower shelf in the same figure. To guide the shelves as they slide in and out and also to support the same when adjusted out, as shown at the top of Fig. 1 and at the bottom of Fig. 2, I provide the links E and F, which are 45 jointed together at G, the link E being piv-

oted at its upper end at e to the frame and 50 abutting a stop e' to limit the outward movement of the shelf C. The link F is jointed at G to the lower end of the link E and at f to the shelf C, near the outer end of said shelf. When the shelves are adjusted outward, it will be understood their outer ends will be braced by the links, which will steady the movements of the shelves as they are adjusted both out and in in the use of the invention. When the shelves are adjusted out, 55 as shown at the bottom of Fig. 2, to permit access to the cracker-box H, resting thereon, the weight of the box has a tendency to cause the shelf C to dip at its outer end, moving in slightly at such time, and to overcome this tendency I provide means for locking the shelf when adjusted to its outer position and also for locking the shelf when adjusted inward to the position shown at the top in Fig. 2 in order to prevent unauthorized 60 persons from tampering with the boxes of crackers. This is preferably accomplished by the construction shown, in which the bolts I are actuated outwardly to enter the seats D or D' by means of the spring i, and said bolts 65 are retracted by means of the handle-bar J, sliding in guides j and connected at its inner end by links K with the bolts I, so the bolts can readily be retracted, as indicated in dotted lines, Fig. 3, by drawing the handle-bar J to 70 the front. As shown, the bolts I and their springs i are preferably made integral and of a suitable length of spring-wire bent to furnish the bolts I, the springs i having the spur i' and the stud i'' to facilitate connection with 75 the links K, as will be understood from Figs. 3 and 4 of the drawings. When the shelves are closed, as shown at the left in Fig. 1, and it is desired to draw them outward to the position shown at the right in said figure, it is 80 only necessary to pull slightly upon the handle-bar J, which will release the bolts I from engagement with the case and permit the forward movement of the shelves to expose the cracker-boxes, as shown in Fig. 2. When 85 the shelves are moved outward to the full extent, the bolts I engage in the seats D' and prevent any retrograde movement of the

shelves and also prevent any dipping of the shelves at their outer ends by the weight of the boxes supported thereon.

Having thus described my invention, what I claim as new, and desire to secure by Letters Patent, is—

1. A cracker-case substantially as herein described comprising framing having guides for sliding shelves, and provided with inner 10 and outer seats for engagement with locking devices, and shelves sliding in said guides, links jointed together at one end, one of said links being jointed at its outer end to the shelf and the other link being jointed at its 15 upper end to the framing, a stop for the latter link whereby to limit the outward movement of the sliding shelf, and locking devices supported on the under side of the shelves and including sliding handle-bars, the bolts 20 and their actuating-springs, and links connecting said bolts with the sliding handle-bars substantially as set forth.
2. A cracker-case comprising the framing having guides for shelves, shelves sliding in 25 said guides, locking devices for said shelves, and links for guiding and bracing said shelves substantially as set forth.
3. The combination in a cracker-case of the framing having guides for shelves, the sliding shelves, the links arranged in pairs, the 30 links of each pair being pivoted together at one end and one of said links being pivoted at its upper end to the framing and the other one of said links being pivotally connected at 35 its outer end with the outer end of the sliding shelf substantially as set forth.
4. The combination in a cracker-case of the

framing having guides for shelves, the shelves sliding in said guides, and the locking devices carried by said shelves and comprising the 40 sliding handle-bar, the bolts and their actuating-springs, and the links connecting said bolts with the handle-bar substantially as set forth.

5. A cracker-case comprising the framing 45 having guides for sliding shelves and provided with inner and outer seats for locking devices, the sliding shelves operating in said guides and the locking devices carried by the shelves and engaging with the inner and outer 50 seats of the case substantially as set forth.

6. A cracker-case comprising the framing having guides for sliding shelves and notches at the inner and outer ends of said guides combined with the shelves, and the bolts carried by the shelves and engaging the notches 55 substantially as set forth.

7. The improvement in cracker-cases comprising the frame having grooves for sliding shelves, the sliding shelves operating in said 60 grooves, the links for guiding and steadyng said shelves, and the lock devices for said shelves substantially as and for the purposes set forth.

8. A cracker-case, comprising framing having guides for shelves, shelves sliding in said guides, links pivoted together at their meeting ends, and connecting the shelves and framing, and devices for locking said shelves. 65
